UNITED STATES PATENT OFFICE

158,807

GAME BOARD

Joseph Oscar Séguin, Montreal, Quebec, Canada

Application April 6, 1949, Serial No. 1,825

Term of patent 14 years

(Cl. D34—5)

To all whom it may concern:

Be it known that I, Joseph Oscar Séguin, citizen of Canada, residing at 1669A Laurier Street, city of Montreal, Province of Quebec, Canada, have invented a new, original, and ornamental Design for Game Board, of which the following is a specification, reference being had to the accompanying drawing, forming part thereof.

The figure is a plan view of a game board showing my new design. The board is of conventional thickness.

I claim:

The ornamental design for a game board, as shown and described.

J. OSCAR SÉGUIN.
